ELECTRIC CABLE

Walter T. Peirce, Worcester, Mass., assignor to
 The American Steel and Wire Company of New
 Jersey, a corporation of New Jersey

Application January 15, 1946, Serial No. 641,204

7 Claims. (Cl. 174—13)

1

This invention relates to an electric cable of the type shown in my co-pending application, Serial No. 507,693, filed October 26, 1943, now Patent No. 2,398,447, dated April 16, 1946, of which this application is a continuation-in-part.

In this type of cable, the electrical conductors and insulation are enclosed in an oil tight sheath. Due to temperature changes the pressure within the cable will vary if compensating means are not provided. This causes trouble due to ionization and also distortion and breakage of the sheath. Various compensating means have been proposed, but they have not proved satisfactory for all purposes.

It has been proposed to use capillary tubes but they have certain limitations. It has been found that it is difficult to effect stabilization over long lengths of cable such as one or more miles in length through tubes of capillary size. A single capillary tube cannot contain a large amount of oil and therefore it is necessary to use a plurality of such tubes in order to take care of large temperature or pressure changes.

With the cables now in use there is the possibility that the pressure within the cable will fall below atmospheric. This condition is undesirable and it is an object of this invention to provide an electric cable in which the pressure of the oil will always be above atmospheric.

Another object is to provide an electric cable having means for keeping the pressure throughout the length of the cable constant.

Still another object is to provide pressure compensating means which can be easily incorporated in various types of cables having oil saturated insulation.

These and other objects will be more apparent after referring to the following specification and attached drawings, in which:

Figure 1 is a cross sectional view of the cable;

Figure 2 is a schematic drawing showing one pair of tubes within the cable with joints between successive lengths of cable;

Figure 2a is a fragmentary view similar to Figure 2, but showing a modification of my invention; and

Figure 3 is a view similar to Figure 1, but showing a modification of my invention.

Referring more particularly to the drawings, the reference numeral 2 indicates the metallic conductors of the cable, each of which is surrounded by oil impregnated insulation 4. A metallic tape 6 surrounds the insulation 4 and a metallic and fibrous binder 8 holds the three conductors 2 together and makes contact between

the metallic tape 6 and the impervious sheath 10 which surrounds the entire cable. Between the conductors 2 are a plurality of concentric tubes 12 and 14. The space in the interstices 5 between the conductors not occupied by the concentric tubes 12 and 14 is filled with fibrous material 16.

Figure 2 is a schematic representation drawn out of scale to illustrate the operation of the 10 system when several lengths of cable constructed as in Figure 1 are joined together. The conductors and insulation are omitted from the drawing for the sake of simplicity. The outer tube 12 is provided with openings 18 at spaced apart intervals for a purpose which will appear later. The lengths of cable are spliced together at the 15 enlarged section 20. Within this enlarged section 20 is a manifold 22 which joins the ends of the two adjacent sections of the outer tube 12. The ends of the inner tubes 14 are open to the manifold 22. Instead of using a separate manifold 22, the contiguous outer tubes 12 of each 20 length of cable may be spliced together by means of a splicing sleeve 23 and the inner tubes 14 25 broken at the splice as shown in Figure 2a so that the gas therein will have access to the space between the tubes. In other words the splice acts as the manifold.

In the manufacture of the cables, the inner 30 tube 14 is first extruded from copper or other flexible material and the outer tube 12 is then extruded from similar material around the outside of tube 14 and perforated at intervals. The conductors 2 are covered with the insulation 4 35 which may be helically applied paper tape. The three conductors 2 and the three pairs of tubes 12, 14 are put on separate cradles and cabled together in the usual manner by rotating the cradles as the cabled conductors are advanced. 40 The assembly is then placed in a tank and the inner tube 14 is flushed out with an inert gas such as nitrogen and sealed off. Heat and vacuum are applied to the cable to remove all 45 gas and moisture and the tank is filled with an insulating oil to impregnate the insulation 4. This oil will enter the openings 18 and fill completely the space between the tubes 12 and 14, as well as all other voids within the cable structure. The protective sheath 10, which is generally 50 made of lead, is then extruded over the cable. The cable is made up in lengths convenient to handle, such as 500 feet, and several such lengths are fastened together to provide the total length required. At each joint 20 the outer tubes 12 55 are connected to the common manifold 22. The

seals are removed from the ends of the inner tubes 14 which are then open to the manifold 22.

When the cable changes in temperature due to atmospheric changes or heating, the components of the cable expand. The pressure developed causes the liquid with which the cable was impregnated to enter the openings 18 and flow along the space between the tubes 12 and 14 toward manifold 22 which will fill with oil coming from both directions and finally enter the open ends of tubes 14. Since tube 14 is small, the oil will block the cross section of the tube due to the wetting tension between it and the wall of the tube and prevent the gas from escaping. Additional oil will gradually compress the gas originally in tube 14 between the oil blocks entering both ends. Thus the gas in the tube 14 will act as a cushion to provide space in the cable structure to take care of the expanding liquid without undue pressure change. When the cable cools off, the compressed gas in tube 14 will force the liquid back to the manifold 22, through the space between tubes 12 and 14, and through the openings 18 back into the cable structure.

Figure 3 shows a pair of tubes 24 and 26 which serve as the core of a single conductor cable. The conducting wires 28 are cabled about the pair of tubes 24 and 26. Oil impregnated insulation 30 surrounds the conductor and a protective sheath 32 is extruded around the entire cable. In this embodiment, the tubes 24 and 26 function in the same manner as tubes 2 and 14 and the above description of Figure 2 is equally applicable to this second embodiment if reference numerals 24 and 26 are substituted for reference numerals 12 and 14. The description of the operation of the pressure compensating means for Figures 1 and 2 is equally applicable to this embodiment.

While two embodiments of my invention have been shown and described, it will be apparent that other adaptations and modifications may be made without departing from the scope of the following claims.

I claim:

1. A cable comprising a conductor, insulation about the conductor including a liquid, a fluid-tight sheath about the insulation, a tube containing gas disposed within said sheath, an outer tube surrounding and substantially parallel to the first tube and providing a space therebetween, said outer tube having an opening therein for admitting liquid thereto, and a manifold, said outer tube terminating in said manifold, said inner tube opening into said manifold whereby the liquid upon expansion will enter into said inner tube and compress the gas therein.

2. A cable comprising a conductor, insulation about the conductor including a liquid, a fluid-tight sheath about the insulation, a tube containing gas disposed within said sheath, an outer tube surrounding and substantially parallel to the first tube and providing a space therebetween, said outer tube having openings therein at spaced intervals for admitting liquid thereto, and a manifold at each end of the outer tube, said inner tube opening into said manifold whereby the liquid upon expansion will enter into said inner tube and compress the gas therein.

3. A cable comprising a conductor, insulation

about the conductor including a liquid, a fluid-tight sheath about the insulation, a plurality of tubes containing gas disposed within said sheath, an outer tube surrounding each of said tubes and substantially parallel thereto and providing a space therebetween, said outer tubes having openings therein at spaced intervals for admitting liquid thereto, and a manifold at each end of the outer tubes, said inner tubes opening into said manifold whereby the liquid upon expansion will enter into said inner tubes and compress the gas therein.

4. A cable comprising a conductor, insulation about the conductor including a liquid, a fluid-tight sheath about the insulation, a tube containing gas disposed within said sheath, a second tube adjacent said first tube, said second tube having an opening therein for admitting liquid thereto, and a manifold, said second tube terminating in said manifold, said first tube opening into said manifold whereby the liquid upon expansion will enter into said first tube and compress the gas therein.

5. A cable comprising a conductor, insulation about the conductor including a liquid, a fluid-tight sheath about the insulation, a tube containing gas disposed within said sheath, a second tube adjacent said first tube, said second tube having openings therein at spaced intervals for admitting liquid thereto, and a manifold at each end of the second tube, the first tube opening into said manifold whereby the liquid upon expansion will enter into said first tube and compress the gas therein.

6. A cable comprising a conductor, insulation about the conductor including a liquid, a fluid-tight sheath about the insulation, a plurality of tubes containing gas disposed within said sheath, a tube adjacent each of said first named tubes, each of said last named tubes having openings therein at spaced intervals for admitting liquid thereto, and a manifold at each end of the last named tubes, the first tubes opening into said manifold whereby the liquid upon expansion will enter into said first tubes and compress the gas therein.

7. A system for the transmission of electrical energy comprising at least two lengths of cable spliced together, each of such lengths of cable comprising a conductor, insulation about the conductor including a liquid, a fluid tight sheath about the insulation, a tube containing gas disposed within said sheath, an outer tube surrounding and substantially parallel to the first tube and providing a space therebetween, said outer tube having an opening therein for admitting liquid thereto, and a splice between the contiguous outer tubes of each length of cable, the inner tube being broken at said splice so that the gas therein has access to the space between the tubes at the splice.
